UNITED STATES PATENT OFFICE.

GEORGE M. HINKLEY, OF MILWAUKEE, WISCONSIN, ASSIGNOR OF ONE-HALF TO ALLIS-CHALMERS COMPANY, OF MILWAUKEE, WISCONSIN, A CORPORATION OF NEW JERSEY.

TIMBER-TRANSFERRING MACHINE.

SPECIFICATION forming part of Letters Patent No. 794,354, dated July 11, 1905.

Application filed May 8, 1905. Serial No. 259,277.

To all whom it may concern:

Be it known that I, GEORGE M. HINKLEY, a citizen of the United States, residing at Milwaukee, in the county of Milwaukee and State of Wisconsin, have invented certain new and useful Improvements in Timber-Transferring Machines, of which the following is a specification.

This invention relates to timber-transferring machines.

The object of the improvement is to pile flitches of various widths upon the saw-carriage, so that they can all be forced snugly against the knee of the carriage.

In the manufacture of lumber it is sometimes necessary to transfer unfinished or partly-finished timber from a storage location to the saw-carriage for further operation thereon. Such partly-finished timber usually exists in the form of flitches which have been cut for the purpose of quarter-sawing or resawing and is temporarily stored to be worked up when a sufficient number of flitches has accumulated. In such finishing operation a number of flitches is piled upon a saw-carriage, so that they all individually contact with the knees of the carriage. After being so piled they are set out sidewise by the knees operated by the set-works, so that the opposite edges, which may or may not be in vertical alinement, may be operated upon by the saw. Generally stated, the flitches are brought to the final operation of the saw by being first conveyed to the vicinity of the live rolls by a lumber-carrier. The carrier deposits the flitches upon the upper edges of skids. These skids are then raised to the necessary height above an adjacent saw-carriage, and a push-arm is then brought into operation to shove the flitches from the skids onto the saw-carriage and against the knees of the carriage.

In the drawings, Figure 1 is a side view of the machine, parts of the frame being shown in section. Fig. 2 is an end view of the machine looking from the right in Fig. 1 and omitting the carriage and carrier. Fig. 3 is a plan view, enlarged, of the finger pivoted to the upper end of the push-arm; and Fig.

4 is an elevation, partly in section, on line 41 of Fig. 3 of the finger and upper end of 50 the push-arm.

A carrier 1 is shown (see Fig. 1) as an endless belt or series of belts running upon pulleys 2 3. Power is communicated to the carrier from any convenient source by means of 55 a belt 4, running upon a pulley mounted upon the same shaft as pulley 3. A flitch 5 is shown in Fig. 1 as entering into coaction with the carrier 1, so as to be conveyed thereby into the vicinity of the live rolls 6. These 60 live rolls 6 are shown intermediate the delivery-pulleys 2 of the carrier and the saw-carriage 7. The live rolls are shown conventionally only, as they specifically form no part of the invention.

Referring to Fig. 2, skids 8 are mounted each between consecutive live rolls, so as to slide vertically, guides 9 (see Fig. 1) being provided therefor upon the frame 10. The lower ends of the skids are pivotally mounted 70 upon the skid-shaft 11, which is supported upon oscillating arms 12, clamped at their opposite ends upon a rock-shaft 13. The rock-shaft 13 is mounted in another part of the frame 101. To the oscillating end of one of 75 the arms 12 (that shown at the left in Fig. 2) is pivotally connected connecting-rod 14, which at its other end is connected to piston-rod 15 of cylinder 16. The operation of this piston-rod and connected parts is under the 80 control of the operator by ordinary valve connections 17. (Shown in Fig. 1 and omitted for convenience in Fig. 2.)

Thus far described the mechanism provides for vertically actuating the skids 8 under the 85 control of the operator. In addition to such vertical operation of the skids 8 means must be provided for shoving off from the skids the flitches elevated thereby. Such means consists of a push-arm 18, pivotally mounted 90 upon the skid-shaft 11 at its lower end and free to be swung about the skid-shaft as an axis by means under control of the operator. This operating means for the push-arm includes a connecting-rod 19, at one end pivoted 95 to the push-arm intermediate its ends and at

the other end connected to piston-rod 20 of cylinder 21, mounted upon a part of the frame 102. The reciprocation of the piston-rod 20 is under the control of the operator by ordinary valve-gear 22, actuated by means of operating-handle 23.

As thus far described the operation of the push-arm is brought about by admitting steam to one end or the other of the cylinder 21, following which the piston-rod 20 will communicate its motion to the push-arm 18 through the connecting-rod 19, causing the push-arm 18 to swing about the skid-shaft 11 as an axis. The limit of motion of the push-arm, if constructed only as thus far described, would be when the said arm approaches into proximity to the saw-carriage 7. The flitches therefore could not be positively pushed into contact with the knees 24.

In order to provide means for positively shoving the flitches into contact with the knees 24, a finger 25 is provided. This finger 25 is pivoted to the upper end of the push-arm 18, as clearly indicated in Figs. 3 and 4. The pivoted end of the finger is formed into three tangs, as shown in Fig. 3, coacting with similar tangs on the push-arm. The middle tang 26 is of a peculiar configuration, (see Fig. 4,) adapted in the position shown in Fig. 4 to limit the lowermost position of the finger by resting the same upon the abutment 27 formed in the upper end of the push-arm 18. To adjust the finger in its lowermost transverse position on the push-arm, a set screw (not shown) may be passed from below through the abutment 27 of the push-arm 18, threading in the latter and provided with a lock-nut, if necessary. The push-arm 18 is formed with a groove 28, Fig. 4, at its center, so as to provide an abutment 29, which coacting with the lower edge of the tang 26 limits the uppermost position of the finger 25. The finger 25 is therefore limited in its oscillation with reference to the push-arm 18. The purpose of this will hereinafter appear.

At the free end of the finger 25 is provided a chisel-point 30, (see Figs. 3 and 4,) which has a square shank 31 snugly fitting a square opening in the end of the finger. A pin 32, extending through the finger 25 and chisel-shank 31, is riveted fast in the finger 25 and serves to hold the chisel-point firmly in position in the finger 25.

The lowermost position of the finger 25 as to its oscillation in reference to the push-arm 18 is so designed that the chisel-point 30 will describe a path when the push-arm 18 is oscillated which will be a short distance above the plane of the upper ends of the skids 8 in whatever position the skids may be. This short distance is designed to be approximately one-half the thickness of a flitch. With such design of parts the chisel-point 30 will "take" in a flitch resting upon the skids 8 at any elevation of the skids 8. This will follow from

the fact that the push-arm 18 is mounted upon the skid-shaft 11. When the piston-rod 15 is reciprocated, the arms 12 are correspondingly oscillated and skid-shaft 11 is correspondingly elevated, and the skids 8, together with the push-arm 18, both mounted upon the skid-shaft 11, are correspondingly elevated with the skid-shaft 11. In this way the skids 8 and the push-arm 18 are always kept in the same relative vertical position, or, in other words, at the same elevation. The peculiar pivotal connection between the finger 25 and the push-arm 18 at the same time keeps the chisel-point 30 in proper working position with relation to the skids 8 and any flitches that may rest thereon.

In the operation of the entire device as described the flitch 5 is brought to the transferring-machine by means of the endless carrier 1. It is then dropped onto the skids 8, which by proper manipulation of the valve-gear 17 of the cylinder 16 are brought slightly above the live rolls. The flitch thus rests quietly upon the upper ends of the skids 8, being unaffected by the live rolls 6. In fact, during the operation of the transferring-machine the live rolls are not in operation. It is therefore unnecessary to certainly locate the upper ends of the skids 8 slightly above the live rolls 6, the flitches dropping either upon the upper end of the skids or upon the rolls 6. The operator now raises the skids 8 by suitable manipulation of the valve 17 of cylinder 16, so that the flitch carried by the skids 8 is sufficiently elevated to clear the saw-carriage 7 or any flitches 51 that may previously have been placed upon the saw-carriage 7. The push-arm 18, which up to this time is in a position to the extreme right, as shown in Fig. 1, is now brought into operation by a proper manipulation of the handle 23, controlling the valve-gear 22 of the cylinder 21. The push-arm 18 is thrown to the left of its position shown in Fig. 1, the chisel-point 30 "taking" in the side of the flitch resting upon the skids 8, and the flitch is thus pushed off the skids 8 and either onto the saw-carriage 7 or on top of a flitch 51, previously shoved onto the saw-carriage 7. In either case and independent of the width of the flitch it is shoved in contact with the knee 24 of the saw-carriage, so that all the flitches piled upon the saw-carriage will rest snugly in contact with the knees 24. After the push-arm 18 has served its purpose it is designed to be withdrawn by proper operation of piston-rod 20 of steam-cylinder 21; but should it be neglected to bring about such operation and the skids 8 be lowered before the push-arm 18 is withdrawn there will be no harm caused by such failure to retract the arm 18, as the finger 25 is pivotally connected to the arm 18. Upon such a descent of the skids 8 without retraction of the push-arm 18 the finger 25 will be swung up upon its pivot until the tang 130

26 comes into contact with the edge 29 of the groove 28, and when this position is reached and upon further descent of the skids the push-arm 18 will be forced back by the contact of the finger 25 with either the edge of the saw-carriage 7 or the projecting edge of the ditch 51 upon the saw-carriage. Of course it will be necessary to retract the push-arm 18 before the skids are again elevated.

10 In order to stiffen the rock-shaft 13 and skid-shaft 11, a connecting-arm 112 (see Fig. 2) is arranged near the middle of these shafts, so as to firmly space the same at their given distance apart.

15 In accordance with the provisions of the patent statutes the principle of operation of the invention has been described, together with the apparatus which is now considered to represent the best embodiment thereof; but it is 20 desired to be understood that the apparatus shown is merely illustrative and that the invention can be carried out by other means.

What I claim is—

1. The combination with vertically-guided power-operated skids, a horizontally-power-operated push-arm, a plurality of independent manual controlling means for controlling the movements of the skids and push-arm respectively, and a finger mounted upon the 30 push-arm.

2. The combination with the saw-carriage, of a timber-carrier, rolls between the saw-carriage and the carrier, a timber-transferring means comprising power-operated vertically-guided skids between the rolls, a power-operated push-arm mounted to project above the skids and to move between the carrier and the saw-carriage for transferring the timber sidewise off the skids to the saw-carriage, and a 35 finger pivotally mounted upon the push-arm.

3. In a timber-transferring machine, a horizontal skid-shaft, vertically - power - actuated skids on the skid-shaft, a horizontally and independently power actuated push-arm on the 40 skid-shaft, and a finger pivotally mounted at the upper end of the push-arm.

4. In a timber-transferring machine, a horizontal skid-shaft, vertically - power - actuated

skids on the skid-shaft, a horizontally and independently power actuated push-arm on the 50 skid-shaft, a finger pivotally mounted at the upper end of the push-arm, and means for transversely positioning the finger at its lowermost limit of motion on the push-arm.

5. In a timber-transferring machine, a vertically - power - actuated skid - shaft, skids mounted thereon, a push-arm also mounted thereon intermediate the skids, independent power means for horizontally actuating the push-arm, and a finger pivotally mounted at 60 the upper end of the push-arm.

6. In a timber-transferring machine, a vertically - power - actuated skid - shaft, skids mounted thereon, a push-arm also mounted thereon intermediate the skids, independent power means for horizontally actuating the push-arm, a finger pivotally mounted at the upper end of the push-arm, and means for transversely positioning the finger at its lowermost limit of motion on the push-arm. 70

7. In a timber-transferring machine, power-actuated means for vertically raising lumber, means for carrying lumber to said raising means, and independently - actuated power means including a pivotally-mounted finger 75 for horizontally pushing the lumber thus raised.

8. In a timber-transferring machine, means for delivering lumber to the transferring-machine, separate means for raising the lumber 80 thus delivered, and independently - operated means including a pivotally-mounted finger for pushing sidewise the lumber thus raised.

9. In a timber-transferring machine, means for raising lumber, separate means for delivering lumber to the raising means, and independently-operated means including a pivotally-mounted finger for pushing sidewise the lumber thus raised. 85

In testimony whereof I affix my signature in 90 presence of two witnesses.

GEORGE M. HINKLEY.
